(57) **CLAIM**

The ornamental design for a mobile phone, as shown and described.

DESCRIPTION

1. Mobile phone

1.1 : Front

1.2 : Back

1.3 : Right

1.4 : Top

1.5 : Bottom

1.6 : Perspective

1.7 : Perspective

Reproduction 1.1 is a front elevation view of a mobile phone, showing a slider phone of our new design in an extended state; reproduction 1.2 is a rear elevation view thereof; 1.3 is as right side elevation view thereof; reproductions 1.4 and 1.5 are top and bottom plan views thereof; and reproductions 1.6 and 1.7 are two perspective views thereof.

1 Claim, 5 Drawing Sheets
